UNITED STATES PATENT OFFICE.

EARL F. PIERCE, OF CHICAGO, ILLINOIS, ASSIGNOR TO ALEMITE MANUFACTURING CORPORATION, OF CHICAGO, ILLINOIS, A CORPORATION OF DELAWARE.

LUBRICANT COMPRESSOR.

Application filed April 21, 1924. Serial No. 708,007.

My invention relates to improvements in lubricant compressors, and is particularly concerned with improvements in that type of lubricant compressor which is used for 5 supplying lubricant under pressure to a plurality of fittings, the compressor including a coupling member for successively making sealed contact with the various fittings.

Compressors of the character described 10 above are usually so constructed that the coupling member can be detached from the barrel portion of the compressor so as to permit the escape of air therefrom during the filling operation. In some cases, a flexible hose is 15 interposed between the coupling member and the barrel, but with this construction, as well as with the construction in which the coupling member is directly secured to the barrel, the coupling member and the combined hose and 20 coupling member are usually removed from the compressor barrels before the latter are filled.

One of the objects of my present invention is to provide a compressor of the character de- 25 scribed, in which the coupling member or the flexible discharge conduit is connected to the compressor barrel in such manner that it need not be removed from the compressor barrel during the filling operation, but, never- 30 theless, permits the free discharge of air from the compressor barrel.

Another object of my invention is to pro- 35 vide a lubricant compressor having a dis- charge conduit or coupling member connected therewith by a swivel connection, and in which a portion of the compressor barrel itself acts as one of the swivel members.

My invention further contemplates the 40 provision of a lubricant compressor, such as described above, which is simple in construction, economical to manufacture, and easy to operate.

Other objects of my invention will appear 45 from time to time as this description progresses, reference being had to the accompanying drawings, in which

Figure 1 is a side elevation, partially in 50 longitudinal section, of a compressor embodying my improvements;

Figure 2 is an enlarged sectional detail, and

Figure 3 is an exploded view, partially in 55 longitudinal section and partially in elevation, disclosing a modified form of my invention.

Referring to the drawings, and for the present to Figures 1 and 2, I have illustrated my invention in combination with a compressor comprising the barrel 5 having the removable cap 6, through which extends the 60 threaded piston rod 7 carrying the piston 8 at its inner end, and the handle 9 at its outer end.

At its opposite end, the barrel 5 is provided with an integral closure 10 having the tubular extension 12 formed integrally therewith. This extension has an angularly extending flange 13 provided with a central aperture for receiving the tubular portion 14 of the swivel member 15, which is rigidly 70 secured to the inner end of the flexible discharge conduit 16.

The inner end of the tubular member 14 is provided with a head 17, between which and the flange 13 is confined the washer 18, the 75 bottom of the cup leather 19 and a second washer 20.

A compression spring 21 yieldingly holds the parts just described in the position shown in Figures 1 and 2, so that the cup leather 19 80 effectually prevents the escape of lubricant between the tubular member 14 and the adjacent portions of the compressor barrel.

At one point in its circumference, the opening which receives the tubular member 14, is 85 enlarged, as shown at 22 (see Fig. 2) to provide an air vent. When it is desired to fill a compressor barrel, such as described herein, the cap 6 is removed and the open end of the barrel is inserted in a supply of lubricant, or 90 pushed against the perforated follower of a lubricant can, which is now upon the market and well known to those skilled in this art, and pressure is applied to the knurled portion of the swivel member 15 in a direction toward 95 the supply of lubricant, whereupon the spring 21 is compressed and the tubular member 14, the cup leather 19, and the associated parts move to the position shown in dotted outline in Figure 2, thereby permitting air to escape 100 from the cylinder 5 and lubricant to enter the same. It will, of course, be understood that this air escapes through the air vent 22.

Where it is desired to fill the compressor barrel by means of a knife, spatula, or other 105 similar implement, the portion of the discharge conduit 16 immediately adjacent the swivel member 15 can be rested upon any suitable support, and by pressing downwardly upon the barrel 5, the user can cause the 110

parts just described to move to the position shown in Figure 2, thereby facilitating the discharge of air from the bottom of the compressor.

- 5 From the above description, it will be apparent that, in addition to providing means for facilitating the discharge of air from the compressor barrel during the filling operation, I have also provided a connection between the flexible conduit 16 and the compressor barrel which functions as a swivel. This is desirable as it prevents twisting stresses being placed upon the conduit 16 while the compressor is in operation, and 10 thereby materially lengthens the life of this conduit. I have illustrated this conduit as terminating in a coupling member 24, of well known construction, further description of which is unnecessary.
- 15 20 In some types of compressor, the coupling member 24 is connected directly to the barrel 5. Substantially the same result can be accomplished by my improved construction by connecting this coupling member 24 directly 25 to the swivel member 15'.

In Figure 3, I have illustrated a construction which permits the flexible conduit 16 to be easily and quickly attached to or detached from the compressor barrel, and 30 which, at the same time, functions as a swivel. In this modified form of my invention a pair of oppositely disposed spaced tongues 25, only one of which is shown in the drawings, are formed integrally with the tubular extension 12 and then bent at right angles to the tubular extension and to the axis of the compressor, as shown in Figure 3, to provide means for receiving the head 18' of the swivel member 15', which is secured to the 35 inner end of the flexible conduit 16. Preferably the tongues 25 are provided with slight projections 26 which engage the edge of the head 18' and tend to hold it in assembled relation with the compressor barrel when the head 18' is received between the tongues 25.

40 For sealing the connection between the swivel member 15' and the compressor barrel, I provide the thimble 27 which has formed integrally therewith the inner flange 28, having the central aperture 29 and the comparatively narrow outer flange 30. A gasket 31 of leather or other suitable material rests against the flange 30, and is yieldingly held thereagainst by means of the compression 45 spring 32 confined between the flange 28 and the gasket 31. When the swivel member 15' is connected with the compressor barrel, as described above, the spring 32 holds the central portion of the gasket 31 in tight contact 50 with the head 18' of the swivel member 15', and thereby prevents the escape of lubricant between these two members. As pressure is applied to the lubricant by means of the screw threaded piston rod 7 and the piston 8, this

5 pressure increases the sealing effect between the gasket 31 and the head 18'.

When the operator desires to fill a compressor, constructed as shown in Figure 3, he removes the swivel member 15' therefrom, and then proceeds to fill the compressor as described above, or in any other suitable way, and the air escapes through the openings in the flange 28 and the gasket 31. When the compressor has been refilled, the swivel 15' can be snapped into place, and the compressor 75 is then ready for further use. It will be seen that in this modified form of my invention, there is a swivel connection between the member 15' and the compressor barrel, which serves the same function as that described in 80 connection with Figures 1 and 2.

While I have described the details of construction of the preferred embodiment of my invention, it is to be clearly understood that my invention is not limited to these details, 85 but is capable of other adaptations and modifications within the scope of the appended claims.

Having thus described my invention, what I claim is:

90 1. A lubricant compressor comprising a barrel, a swivel member formed integrally with said barrel, said member having a vent passage, a coupling member, and a swivel member connected with said coupling member and coacting with the swivel member on said barrel to form a swivel connection between said coupling member and said barrel, said swivel members comprising means, when in one position, for permitting the escape of air from said barrel through said vent passage and, when in another position, preventing leakage from said barrel.

95 2. A lubricant compressor comprising a barrel, a discharge conduit, and means forming a connection between said discharge conduit and barrel permitting swivel movement without leakage, and manually operable to vent the system at the connection.

100 3. A lubricant compressor comprising compressing means, a discharge conduit, swivel members rotatable and axially slidably and connecting said conduit and compressing means, and venting means rendered operable by axial sliding movement of said swivel 105 members.

110 4. A lubricant compressor comprising compressing means, a discharge conduit, swivel members connecting said conduit and compressing means, and manually operable means 115 for opening a vent passage at the swivel connection.

120 5. A lubricant compressor comprising a barrel, a discharge conduit for said barrel, and swivel means comprising two co-acting 125 elements, one on said barrel and one on said discharge conduit, said swivel means permitting rotative movement between said con-

duit and said barrel, said co-acting elements being relatively reciprocable between two positions and permitting passage of lubricant from said barrel to said conduit in both positions and discharge from said barrel to the atmosphere only when in one of said positions.

6. A lubricant compressor comprising a barrel having a removable closure at one end, 10 a closure for the other end having a tubular extension, an inwardly extending flange at the outer end of said tubular extension, said flange formed to provide a vent opening, a

discharge conduit having a tubular member swiveled upon said flange and reciprocable 15 relatively thereto, said tubular member always in communication with said barrel, a sealing member reciprocable with said tubular member for sealing the joint between said tubular member and said tubular extension in 20 one position and for opening said vent in another position, and a spring for holding said sealing member in sealing position.

In witness whereof, I hereunto subscribe my name this 16th day of April, 1924.

EARL F. PIERCE.
